HIS ATTORNEYS.

UNITED STATES PATENT OFFICE.

FREDERICK W. HEDGELAND, OF CHICAGO, ILLINOIS, ASSIGNOR TO THE
W. W. KIMBALL COMPANY, OF SAME PLACE.

FALL-BOARD FOR MUSICAL INSTRUMENTS.

SPECIFICATION forming part of Letters Patent No. 594,012, dated November 28, 1897.

Application filed September 17, 1897. Serial No. 652,020. (No model.)

To all whom it may concern:

Be it known that I, FREDERICK W. HEDGELAND, a citizen of the United States, residing in Chicago, in the county of Cook and State 5 of Illinois, have invented a new and useful Improvement in Fall-Boards for Musical Instruments, of which the following is a specification.

This invention relates to the construction 10 of a fall-board capable of being folded upon itself and moved into a recess in the case of the instrument.

The invention consists in the novel features of construction shown in the accompanying drawings and set forth in the claims.

The drawings show at Figures 1 and 2 vertical sections of the fall-board and the adjacent parts of the instrument, the fall-board being shown in different positions in the two 20 figures.

In said drawings, A represents one of the ends, B the front, C the finger-board, and D the top, of the instrument-case. E E are the keys. The fall-board is composed of three 25 sections F, G, and H, the latter being the inner section and pivotally attached at each end to swinging levers J. Each lever J is supported upon a pivot K, secured in the end of the case or otherwise supported. The section H is provided with an upright extension H', which when the instrument is closed sets 30 close under the top D. The middle section G is hinged to the section H at the outer surface of those sections, as at G', so that section G can be folded over upon section H, as shown. The outer section F is hinged to section G at the lower surface of those sections, as at F', so that section F may be folded over 35 upon section G after the latter has been folded upon section H. When thus folded, the three sections lie one on the other, as shown in broken lines in Fig. 1, and the entire fall-board may then be pushed into the recess in the case above the board C and under the top 40 D, as plainly indicated at Fig. 2. The section F is provided with a downward extension F², which when the board is folded, as above described, extends down in front of both of the sections G and H and entirely con-

ceals them from view, so that at such times 50 no hinges or metal parts employed in the fall-board are visible, and as this extension F² may be handsomely veneered or polished it presents a very finished appearance in the folded position. The extension H' and section H are adapted to conceal the opening in the case when the board is unfolded.

One advantage attending my construction is that my improved fall-board when folded enters the case but a short distance, so that 60 the major portion of the space back of the fall-board can be utilized for the sounding devices or action of the instrument.

I claim—

1. The combination in a fall-board, of three 65 hinged sections F, G and H, the front section having an extension adapted to cover the edges of the other two sections when folded, substantially as specified.

2. The combination with an instrument having a recess in its front adapted to receive the folded fall-board, of a fall-board composed of three hinged sections F, G and H, substantially as specified.

3. The combination with an instrument having a recess in its front adapted to receive the folded fall-board, of a hinged fall-board composed of three hinged sections F, G and H and swinging levers J attached to the inner section, substantially as specified.

4. The combination in a fall-board of three hinged sections F, G and H adapted to fold together, as set forth, said section F having a downward extension F², and said section H having an upward extension H', substantially 75 as specified.

5. The combination of an inner section H supported by swinging levers within the case, an intermediate section G hinged at its top to section H, and a front section hinged to section G at its under surface, with a musical instrument having a recess adapted to receive said sections when folded one upon the other, substantially as specified.

FREDERICK W. HEDGELAND.
